THERMIONIC TUBE

Frederick E. Terman, Stanford University, Calif.

Application April 25, 1931, Serial No. 532,742

6 Claims. (Cl. 250—27)

This invention relates to vacuum tubes and vacuum tube amplifier circuits therefor, and particularly to tubes wherein the input or control electrode is operated at a positive potential.

5 Among the objects of this invention are: First, to provide a tube combining a high amplification constant with high mutual conductance and low output resistance; second, to provide a tube which combines a high input impedance with 10 low output impedance; third, to provide a tube which may be operated with a positive bias upon a control electrode without the introduction of appreciable distortion; fourth, to provide a tube wherein secondary emission from the control electrode exercises an advantageous instead of a disadvantageous effect; and fifth, to provide a method 15 of operating vacuum tubes of ordinary construction wherein many of the advantages obtainable from the special tube above mentioned 20 may be realized.

Other objects of this invention will be apparent or will be specifically pointed out in the description forming a part of this specification, but I do not limit myself to the embodiment of this 25 invention herein described, as various forms may be adopted within the scope of the claims.

Referring to the drawing:

Figure 1 is an axial sectional view, and Figure 2 is a transverse sectional view of a triode embodying this invention.

Figure 3 shows graphs illustrating the input impedance of a tetrode of standard construction when operated in accordance with my invention, and when operated in the usual manner.

35 Figure 4 is a schematic diagram of an amplifier circuit embodying a triode and connected in accordance with this invention.

Figure 5 is a similar circuit diagram showing the use of a tetrode in the same manner.

40 Almost all problems of amplifier design have two phases; first, gain, or amount of amplification, and second, linearity, or freedom from distortion. The relative importance of these two phases may differ with the particular amplifier 45 and the service to which it is assigned, but whatever the service both phases must be considered.

Both the requirements for high gain, and that for linearity, require that the vacuum tube which is used in the circuit should have a high input 50 impedance and a low output impedance. Of these secondary requirements high input impedance is usually the more important, since the higher the input impedance the greater the control potential which can be built up across it with a limited amount of input power, and because the

resistance component of the input impedance is not, in general, linear, and if this component be small, i. e., if the conductance be large, serious distortions are introduced. For these reasons it is customary to operate the control grid of a vacuum tube at a negative biasing potential such that the grid is never permitted to become positive. Under these circumstances, the electronic current flowing from filament to grid is sensibly zero, and the resistive component of the impedance may be taken as infinite.

The high input impedance thus gained, is, however, obtained at the expense of low output impedance and high mutual conductance. My invention relates to a method of operating vacuum tube amplifiers wherein the grid is maintained at a positive potential, thereby obtaining the advantages of high mutual conductance, low output resistance, and high amplification constant, without so reducing the input impedance of the tube as to introduce distortion and loss of amplification through absorption of alternating current power by the input circuit of the tube.

Broadly considered, this invention comprises the method of operation of a vacuum tube wherein the potentials of the electrodes are so adjusted that secondary emission of electrons occurs from the control grid, this secondary emission being such that the rate of change in the number of electrons reaching the grid from the filament, with change in grid potential, is substantially equal to the rate of change in the number of secondary electrons drawn from the grid with the same potential changes. The achievement of this end is aided by coating the control grid with a substance facilitating the emission of secondary electrons, such as a substantially monatomic layer of barium or thorium, and the use of such a coating on a control electrode is one aspect of my broad invention. It is to be noted that it is the rate of change of the grid current which is considered; the so-called "static" input resistance of the tube may be relatively low, but if the rates of change of current entering and leaving the grid are substantially equal the dynamic resistance of the grid will be high. Since the power absorbed in the grid circuit due to low static resistance is furnished by a local D. C. source, it is relatively unimportant, falling into the same category as the power absorbed by the D. C. component of plate current. The signal or alternating potential which is to be amplified need therefore supply negligible power to the tube input, and hence

the loss of gain due to this cause is small. While it is possible to use most standard vacuum tubes in accordance with this invention, optimum results are obtained by tubes of special design, the principles of which will now be considered in detail.

Such a tube is shown in Figures 1 and 2, wherein in the usual glass envelope 1 is provided with a stem 2 having leads 3, 5, 6 and 7 sealed through the press 8. The leads 3 and 5 are connected to a filament 10, which is preferably short and heavy so as to present a surface which is large in comparison with its length. The object of this is to obtain a large emission of electrons together with as high a potential gradient as possible adjacent the filament.

Surrounding the filament, and spaced therefrom a considerably greater distance than is customary with tubes used for similar purposes, is a grid 11, which is preferably formed of a large number of turns of fine wire, and which connects to the lead 6. The device is operative if the grid be made of nickel, but its operation is greatly improved if it be coated with a thin layer of material having a very high coefficient of secondary electron emission. Of such materials, the best which has yet been discovered is a monatomic layer of barium, which may be deposited thereon after the tube has been evacuated by distillation from the filament. Other materials such as thorium may also be used for a similar purpose with slightly decreased efficiency. Owing to the extreme minuteness of the secondary emitting layer, no attempt has been made to show it in the drawing, as it is far below microscopic thickness.

A plate electrode 12 is connected to the lead 7, and surrounds the grid. The spacing of this electrode from grid and filament is also preferably greater than that in tubes as ordinarily designed for similar service.

Such a tube is connected in an amplifier circuit in accordance with Figure 4, wherein the signal voltage is indicated as generated by a source 13 which is connected to the filament 10 and grid 11, a biasing battery 15 being supplied in series with the grid to provide a positive charge thereon. The plate 12 is connected through the suitable output impedance 16 through a plate current source 17 and thence back to the filament. For simplicity, the filament supply is omitted in the drawing.

With a barium coated grid 11 of the type described, the positive potential from the source 15 may be of the order of 10 volts. At this voltage, the ratio of secondary electrons to in-falling primary electrons is approximately 1:1.

Obviously, the secondary electrons emitted from the control grid will not all be drawn to the plate of the tube, since their general direction of emission is toward the filament. Some of them will return to the grid and the net effect of these upon the current flowing in the grid circuit will be nil. The design of the grid should be such that as many as possible of the secondary electrons will be projected into the field from the plate, and thus drawn to the plate instead of returning to the grid. This effect is most easily accomplished by using very fine wire in the grid structure. This will result in the greater number of secondary electrons being projected from behind the shielding wires, and thence falling into the stream which reaches the plate, even though their velocity of emission may be small. It is not essential, however, that the secondary elec-

tron emission or the portion thereof drawn to the plate be in the 1:1 ratio. Both of these quantities will vary, not only with the potential of the grid, but also with that of the plate. What is required in order to limit distortion and power absorption in the grid circuit is that the rates of change of the electron current falling onto the grid from the filament, and secondary emission current drawn from the grid be approximately equal. This can easily be achieved, the necessary potentials for any given tube structure being easily found by experiment.

It is not even necessary that the dynamic resistance, representing the ratio of change in grid voltage to change in net grid current be constant, if it be at all times so high as to introduce but a small portion of the total loss in the circuit. The relatively great emitting area of the cathode, and the wide spacing between cathode and grid, permit the establishment of a space charge at 20 the grid potentials used.

Assuming that a space charge is established in the vicinity of the cathode, the plate current of the tube is given an equation of the form

$$i_p = K(E_g + E_p/u)^{3/2}$$

where E_g and E_p are the grid and plate voltages respectively, K is a constant depending on the tube construction, and u is the amplification factor of the tube (i. e., the relative effectiveness upon the electrostatic field produced at the surface of the cathode by voltages applied to the grid and plate). Differentiation of this equation with respect to grid voltage gives the mutual conductance which is therefore

$$g_m = dI_p/dE_g = 3/2K(E_g + E_p/u)^{1/2}$$

It is seen from this equation that in order to have a high mutual conductance the quantity $(E_g + E_p/u)$ should be as large as possible.

Since the grid potential E_g in an ordinary tube is negative, a high mutual conductance can be obtained only by making the quantity E_p/u large, with the result that at a given plate voltage the mutual conductance can be made large only by using a small amplification factor u . This point is well brought out by the usual power tubes used in radio receivers, which gain their high mutual conductance by having a low amplification factor, whereas tubes with higher u and operating at the same plate voltage always have a lower mutual conductance.

In my positive grid tube it is simultaneously possible to obtain a large value $(E_g + E_p/u)$ and a large amplification factor because the grid potential E_g is positive. It is therefore possible to make a positive grid tube having the same mutual conductance as an ordinary power tube but with a much higher amplification factor. Thus analysis of the characteristics of commercial power tubes of the "245" and "250" types show that with the substitution of closely wound high amplification grids, adapted for secondary emission and positive bias, these tubes will supply the same power output for which they are now adapted with only one third of the input voltage.

Although the tube just described is especially adapted to the practice of this invention, ordinary commercial tubes such as are now on the market may also be utilized for this purpose. Figure 5 shows schematically a circuit utilizing a tetrode with a positive control grid to give high input impedance by secondary emission.

The tetrode 20 has the usual cathode 21, inner grid 22, outer grid 23, and plate 25. The control

potential is represented as generated by a source 26, in series with which is a positive biasing potential source 27 connected in series with outer grid 23 and filament 21. The plate is connected 5 through the output impedance 28 and plate supply 30 back to the filament in the usual manner. The inner grid 22 may be operated at the same potential as the cathode, or it may have either a positive or negative bias placed upon it by a battery 31. In the usual tetrode, the spacing of 10 the elements is such that were both grids and the plate operated at positive potentials the electrons from the cathode would be drawn off too rapidly to permit the establishment of a space charge. It is to prevent this effect that the wide 15 spacing between grid and filament is utilized in the form of this invention first described.

Figure 3 shows a curve 35 illustrating the variation 20 in dynamic resistance to the "screen grid" or control grid of a standard tube in such a circuit. The inner grid in this case was operated at cathode potential. It will be seen that for all positive bias voltages between 35 volts and 65 25 volts, the dynamic input resistance to the tetrode is in excess of a half megohm.

Although the dynamic resistance varies over this range, it is still greatly in excess of any resistance across which it would ordinarily be connected, so that any distortions introduced into the 30 circuit by the resistance variations are extremely small.

The high order of the input resistance obtained 35 in this manner in comparison with the resistances usually obtained with positive grid voltages is shown by comparison of the curve 35 with the curve 36, which shows the input impedance of a tube operated in a similar circuit, but without secondary emission. It will be noted that while the resistance of the secondary emitting tube is in 40 excess of 200,000 ohms for all values of positive grid potential up to 75 volts, the screen grid tube without positive emission shows high impedance only for very small control voltages, the impedance falling rapidly to about 80,000 ohms at voltages where a secondary emitting grid gives ten 45 times this input impedance.

The curve of Figure 3 is given to show the possibilities of my method with standard tubes. Were the grid 23 specially treated to facilitate 50 secondary emission, the dip at about 10 volts would disappear, thus giving very high input impedance at all input voltages up to about 65 volts.

Where this condition obtains it is possible to operate the tube at zero bias without appreciable 55 distortion, the input conductance being zero for the negative half cycles and negligible for the positive. This is of great advantage in eliminating the necessity of any biasing means, such means being extremely troublesome, particularly in 60 power tubes where the biasing voltage must be high.

I am aware that secondary emission has been used in vacuum tubes in order to give negative resistive effects, but such effects are not the ones 65 required for the operation of my invention, which, it will be seen, operates upon a wholly different principle. Moreover, with the exception of such tubes as utilize the negative resistance effect above referred to, it has usually been assumed that 70 secondary emission was a deleterious effect, which was to be avoided from all electrodes, whereas I have here shown that by its proper utilization

greatly increased efficiency may be obtained from properly designed tubes.

I claim:

1. In a vacuum tube circuit, a tube having a control electrode capable of emitting secondary electrons, an anode, an output circuit for said tube connected to said anode, an input circuit for applying a variable potential to said control electrode and separate from said output circuit, and means for applying a positive biasing potential to 10 said electrode such that the rate of change of current to said control electrode and the rate of change of secondary electron current drawn therefrom with changes of potential thereof are substantially equal. 15

2. In a vacuum tube circuit, a tube having a control electrode capable of emitting secondary electrons, and an anode, an output circuit for said tube connected to said anode, an input circuit for applying a variable potential to said control electrode and separate from said output circuit, and means for applying a positive biasing potential to 20 said electrode such that the rate of change of current in the control electrode circuit with changes of potential thereof is materially reduced by secondary emission from said control electrode. 25

3. In a vacuum tube circuit, a tube having a control electrode capable of emitting secondary electrons, and an anode, an output circuit for said tube connected to said anode, an input circuit for 30 applying a variable potential to said control electrode and separate from said output circuit, and means for applying a positive biasing potential to 35 said electrode such that the rate of change of current in the control electrode circuit with changes in potential thereof is reduced by secondary emission to less than 5×10^{-6} amperes per volt.

4. In a vacuum tube circuit, a tube having a control electrode capable of emitting secondary electrons, and an anode, an output circuit for 40 said tube connected to said anode, an input circuit for applying a variable potential to said control electrode and separate from said output circuit, and means for applying a positive biasing potential to 45 said electrode such that the rate of change of current in the control electrode circuit with changes in potential thereof is reduced by secondary emission to less than 2×10^{-6} amperes per volt. 50

5. The method of increasing the effective input 55 impedance of a vacuum tube wherein the variations of potential of a control electrode cause variations of current flowing to a separate anode in an output circuit separate from the input circuit supplying said control electrode, which comprises causing said control electrode to emit secondary electrons at a rate which varies substantially as does the flow of primary electrons to said control electrode. 55

6. The method of increasing the effective input 60 impedance of a vacuum tube wherein the variations of potential of a control electrode cause variations of current flowing to a separate anode in an output circuit separate from the input circuit supplying said control electrode, which comprises applying a positive bias to said control electrode causing said control electrode to emit secondary electrons at a rate which varies substantially as does the flow of primary electrons to said control electrode. 65
